UNITED STATES PATENT OFFICE.

IRA ROBBINS, OF HUGHESVILLE, PENNSYLVANIA.

IMPROVEMENT IN CAR-BRAKES.

Specification forming part of Letters Patent No. **179,350**, dated June 27, 1876; application filed April 7, 1876.

To all whom it may concern:

Be it known that I, IRA ROBBINS, of Hughesville, in the county of Lycoming and State of Pennsylvania, have invented a new and Improved Automatic Car-Brake; and I do hereby declare that the following is a full, clear, and exact description of the same, reference being had to the accompanying drawing, forming part of this specification, in which—

Figure 1 is an end elevation. Fig. 2 is a vertical longitudinal section through the line $x x$ of Fig. 1. Fig. 3 is an inverted plan view. Figs. 4 and 5 are details.

My invention relates to an improved construction of car-brake, designed to apply or remove the brakes automatically or by hand, as may be desired. It consists in the arrangement of a bellows operated continuously by the car-wheels, which is employed for releasing the brakes; in the mechanism operating in connection therewith; and in the devices for automatically applying the brakes by the impact or concussion of the cars, as herein-after more fully described.

In the drawing, A represents the bottom of a car, and B the car-truck, which, together, carry the devices constituting my improved brake.

Pivoted in bearings is arranged a rock-shaft, E, through which the brakes are applied, which is ordinarily effected by a hand-lever, F, fastened in a socket in the said rock-shaft, and projecting up above the platform of the car. Upon the other end of this shaft are arranged two arms, G G', at right angles to each other. G' is loosely attached to a rod, H, and by bearing upon its fixed collar a serves to apply the brakes. This rod H is pivoted below to b' of the two toggle-arms b' b, of which b' has an offset-catch, c, and is bent around beneath a shaft, I, and is pivoted to a slide, d, in which the said shaft I is journaled. The toggle-arm b is pivoted to b' at e, and is pivoted also at the other end fixedly to the plate f, so that a depression of rod H projects the sliding bearing of the shaft I horizontally in its guide-ways. This shaft I carries a friction-wheel, J, with a leather or rubber face, and is also journaled in a fixed bearing, K, and carries a chain, L, which is attached to the rod of the brake. When, therefore, the arm G' depresses

rod H, the bearing of shaft I is projected horizontally, and the friction-wheel J is pressed against the revolving axle of the car-wheels, and the shaft being made to revolve winds up the chain L, and applies the brake-shoes to the wheels. After the brakes are thus applied the catch or offset c is held beneath the latch g, and the brakes thus held to the wheels until the car stops, when they are automatically released. This is effected by the following mechanism: Upon one of the axles of the car-wheels, or upon the wheel itself, are located one or more friction wheels or cams, h, which, in the revolution of the axle, strike against the end of a lever, M, pivoted to the truck, which lever, being backed by a spring, N, is made to vibrate continuously so long as the car is in motion. The other end of this lever is attached to and operates one side, i, of a compound bellows, N', the other side, j, of which bellows is backed by a spring, k, and connected with a tripping-rod, l, which latter operates with the latch g to throw it from the offset and release the brakes. The end of the tripping-rod is made inclined and slides under an arm, m, on the same shaft, n, which carries the latch g. Now, so long as the car is in motion, the side j of the bellows is filled with air, and holds back tripping-rod l, so that a spring, o, holds the latch in position to retain the catch or offset. As soon as the latter is depressed through rod H, the rock-shaft, and hand-lever, the latch receives it, and holds the friction-wheel to the axle, and the brakes are applied until the car is stopped. As soon as the car stops the spring forces the air out of the side j of the bellows, and the tripping-rod slides under the arm attached to the same shaft with the latch g, and as the latter is thrown to one side a tappet, p, affixed to the same throws up the offset or catch and releases the brakes. To throw up the catch requires but a small expenditure of power on the part of the tappet, as the joint e of the toggle-arms will be very nearly in a direct line between the outer pivots of the arms, and just sufficiently below the same not to jolt out from the motion of the car.

To compensate for any irregularities upon the car-axle and insure a uniform and smooth frictional contact between the wheel J and the axle, the frame or plate O, which carries

the wheel J and its co-operating devices, is pivoted at *q* to the truck-frame, and the plate O is provided with a spring, *r*, which makes the pressure of the friction-wheel with the axle always uniform, and prevents slipping of the brakes. Generally the brakes will be applied through the hand-lever; but they may be applied automatically by the concussion or impact of the cars, and for this purpose an arm, P, is rigidly attached to the rock-shaft E, and a slide, Q, is arranged beneath the car in guide-supports R. This slide is held to the front end of the car by means of a spring, S, so that it projects beyond the end of the car, in position to be struck by a similar slide on the opposite car. This slide carries a pivoted plate, T, having a projecting cam, *t*, which, as the slide moves back when the cars come together, strikes the arm P, and, by deflecting it, applies the brakes. By varying the inclination of the cam upon the pivoted plate T, the braking may be variously modified.

As shown in Fig. 2, the cam deflects arm P by the concussion, which arm then passes upon the opposite side of the cam, and the spring S forces the slide back, the brakes being applied and held by this movement.

By turning plate T and increasing the inclination of cam *t*, as shown in Fig. 4, the brakes are applied, but upon the stretching up of the train are immediately removed, the arm being first urged in one direction by the concussion to apply the brakes, and then in the other direction by the same cam, from the action of the spring, which causes a bent rod, *u*, on arm G to strike an arm, *v*, attached to the same shaft with the latch *g* and remove the brakes, the tripping-rod being previously moved out of the way by said arm G. This latter arrangement will be used when going down grade. In backing, the pivoted plate T is turned so that the cam does not strike the arm P.

I am aware of the fact that it is not new to employ a laterally-adjustable shaft carrying a friction-wheel, which engages with the car-

axle to wind up a chain and apply the brakes, and I consequently limit this feature of my invention to the combination of the above devices with the toggle arms *b b'*, whereby the brakes are held applied by reason of the position of the joint *e* with respect to the outer pivots.

Having thus described my invention, what I claim as new is—

1. The shaft I, carrying frictional wheel J, in combination with its sliding bearing *d*, the toggle-arms *b b'*, and the brake with suitable connecting mechanism, for the purpose described.

2. The mechanism for automatically releasing the brakes, consisting of a bellows filled with air by the movement of the cars, and provided with a tripping device, which releases the brakes through the collapsing of the bellows when the cars stop, substantially as described.

3. The combination of the hand-lever F, rock-shaft E, having arms G G', the rod H, having collar *a*, the toggle-arms *b b'*, the catch *c*, latch *g*, plate *f*, and shaft I, carrying the friction-wheel, as and for the purpose described.

4. The combination of the friction-wheel *h* upon the axle, the vibrating lever M, spring N, and compound bellows *N'*, as and for the purpose described.

5. The combination of the bellows *N'*, having tripping-rod *l*, spring-seated arm *m*, shaft *n*, and latch *g*, substantially as and for the purpose described.

6. The plate O, carrying the operating devices, pivoted to the truck-frame at *q*, and having a spring, *r*, as and for the purpose described.

7. The combination, with rock-shaft E, having arm P, of the slide Q, spring S, and pivoted plate T, carrying cam *t*, for automatically applying the brakes, as described.

IRA ROBBINS.
